FISHING LURE

Elmer T. Hajek, 9 S. 731 Brookbank Road, Hinsdale, Ill.

Filed Mar. 11, 1963, Ser. No. 73,904

Term of patent 14 years

(Cl. D31—4)

Fig. 1

Fig. 2

Fig. 3

Fig. 4

Fig. 5

FIG. 1 is a side elevational view of a fishing lure, embodying my new design;

FIG. 2 is a top view thereof;

FIG. 3 is a bottom plan view of FIGURE 1 with the hook portion only fragmentarily shown for convenience of illustration;

FIG. 4 is a front elevational view of FIGURE 1, the hook portion being omitted for convenience of illustration; and

FIG. 5 is a rear elevational view of FIGURE 1, the hook portion being omitted for convenience of illustration.

I claim:

The ornamental design for a fishing lure, as shown.
